UNITED STATES PATENT OFFICE.

FRANZ A. SCHUMACHER, OF EVANSTON, ILLINOIS, ASSIGNOR TO THE QUAKER OATS COMPANY, OF CHICAGO, ILLINOIS, A CORPORATION OF NEW JERSEY.

CHICKEN FEEDER AND SCRAP CONTAINER.

1,403,979.

Specification of Letters Patent. Patented Jan. 17, 1922.

Application filed April 22, 1918. Serial No. 229,962.

To all whom it may concern:

Be it known that I, FRANZ A. SCHUMACHER, a citizen of the United States, residing at Evanston, in the county of Cook and State of Illinois, have invented new and useful Improvements in Chicken Feeders and Scrap Containers, of which the following is a full, clear, concise, and exact description, reference being had to the accompanying drawing, forming a part of this specification.

My invention relates to improvements in chicken feeders, one of the objects of the same being to provide a container into which kitchen scraps may be thrown from time to time, and from which the chickens may, by picking, extract the scraps when the same is placed in the chicken yard, and which at the same time prevents the scraps from becoming scattered on the ground and not only littering up the chicken yard but becoming fouled by the chickens.

For the purpose of illustrating my invention, I have shown one embodiment thereof in the accompanying drawing.

In said drawing, Fig. 1 is a side elevation of a feeder constructed in accordance with my invention;

Fig. 2 is a sectional view on the line 2—2 of Fig. 1;

Fig. 3 is a detail view of the fastening means for the wire;

Fig. 4 is a detail section of the same on the line 4—4 of Fig. 1; and

Fig. 5 is a detail sectional view of the trough showing a drain opening therein.

In said drawing I have shown a container 1, preferably cylindrical in shape and having the sides formed of reasonably wide mesh woven wire.

In constructing this cylindrical container, the wire is cut in suitable lengths and is then turned into a cylinder, the two free ends of the wire being connected together by a suitable sheet metal connecting strip 2. This strip, as will be seen, is provided with a plurality of oppositely disposed integrally-formed lugs 3, which are adapted to pass through the openings in the wire adjacent the free edges, and then be turned back upon themselves to securely clamp the strip to the two edges of the wire. In this way I am enabled to securely connect the two edges of the wire together and at the same time protect the free and cut edges of

the wire in such a manner that the chickens will not be scratched or cut thereby.

The lower edge of the cylindrical container thus formed is inserted in a channel 4 formed near the outer edge of a cone-shaped bottom 5. This cone-shaped bottom preferably consists of a single piece of sheet metal spun in the proper form and having the channel 4 formed therein. The metal bent back in the forming of the channel 4 also provides an annular trough 6.

After the wire has been inserted in the channel, the rim is rolled to clamp the wire in place, thereby securely connecting the bottom and sides of the container together. At suitable intervals around the trough 6 and formed in the channel 4 are openings 7, formed by punching through the metal of the wall, whereby the upset metal made by punching the openings aids in keeping the wire in position and provides drain openings for any moisture in the scraps thrown in the container.

A top 8, preferably cone-shaped and preferably similar in shape to the bottom, is provided, which top has a downwardly extending annular flange 9 adapted to fit over the outside of the wire mesh container.

For the purpose of carrying the container from place to place, I provide a suitable bail 10, the eyes 11 of which fasten into the meshes of the wire of the container. From the above construction it will be observed that I provide an open-mesh container which may be readily placed in the kitchen, into which chicken scraps may be thrown from time to time and which, when placed in the sink, will drain all water off of the scraps thrown in when wet. This container provides a cheap, light and durable device for carrying chicken scraps from the kitchen to the yard, and provides a container from which the chickens, by pecking and pulling and working, extract the scraps for feed, obtaining, by the work in extracting the scraps through the wire netting, the necessary exercise. The container provides a more desirable means for feeding chickens with scraps than scattering the scraps upon the ground, as it prevents the scraps from becoming scattered around the yard, making the chicken yard unsightly, and also prevents the scraps from becoming fouled by the chickens in feeding upon the same. Such scraps and bits as drop off as the

chickens pull at the food while in the container will drop down along the side of the container and be caught in the trough 6 and will not drop on the ground. This trough 5 6 also catches any litter which might drop from the container as it is being carried to the chicken yard. The cone-shaped bottom insures all of the scraps being forced out toward the side of the container irrespective 10 of the amount that is placed in the container, and also assists in draining the water or moisture off of the scraps. The channel 4 not only provides a channel in which the wire mesh is clamped but also acts as a rest 15 to slightly raise the device from the ground and keep the drain openings 7 clear of the ground or clear of the kitchen sink so that the water will drain out.

By making the top cone-shaped, as illustrated, the chickens cannot hop up on top of the container and peck from this position, thereby preventing them from fouling the feed that drops into the trough 6.

The top and bottom are preferably formed 25 of sheet metal spun into the proper form. This sheet metal, however, may be stamped or drawn into proper shape without departing from the spirit of my invention.

Having thus described my invention, what 30 I claim as new and desire to secure by Letters Patent is:—

1. A chicken feed container comprising a body of wire mesh bent to cylindrical form, a bottom for said body formed from a single 35 piece of material to form a cone projecting into the body and having a channel in which the bottom edge of the body fits and an outwardly flaring trough surrounding the outside of the body, the metal of the channel 40 being clamped upon the lower edge of the body to secure the body and bottom together.

2. A chicken feeder comprising a single- 45 piece cone-shaped metal bottom having the metal bent back upon itself to form an annular channel and then outwardly to form

an annular trough, a body formed of wire mesh bent to cylindrical form and having its edges locked together, the lower end of said body being clamped in said annular 50 channel, and a single-piece removable cone-shaped cover for said cylinder having a downwardly extending annular flange fitting over the upper edge of the cylinder.

3. A chicken feed container comprising a 55 sheet of wire mesh bent to bring the ends together to form a cylindrical body, a connector for the adjacent ends of the wire, a cone-shaped bottom projecting into said cylindrical body for forcing the material contained in the body toward the surface thereof, to which the bottom of the lower edge of said wire mesh is secured, and a cover for said cylindrical body secured to the upper edge of said wire and supported mainly by 60 said cylindrical body of wire mesh.

4. A chicken feed container comprising a sheet of wire mesh bent to bring the ends together to form a cylindrical body, a connector for the adjacent ends of the cylindrical body, a cone-shaped bottom projecting into said cylindrical body, to force the material contained in the body toward the surface thereof, and a trough surrounding the exterior portion of the body, said lower edge 75 of the wire being secured to said bottom, and a cover for said cylindrical body secured to the upper edge of the wire mesh and supported mainly by said body of wire mesh.

5. A chicken feed container comprising a 80 reservoir having a side wall and a bottom, and a trough outside said side wall, said bottom having a channel to receive the lower edge of the side wall, said bottom and trough being formed of sheet material, portions of 85 said sheet material being punched in to secure the lower edge of the side wall and to provide drain openings.

In witness whereof, I have hereunto subscribed my name.

FRANZ A. SCHUMACHER.
